[57] CLAIM

The ornamental design for a ceiling fan shroud, as
shown and described.

DESCRIPTION

FIG. 1 is a top perspective view of a ceiling fan shroud,
showing my new design;

FIG. 2 is a bottom perspective view thereof;

FIG. 3 is a top perspective view thereof;

FIG. 4 is an enlarged side elevational view thereof, the
opposite side being a mirror image of that shown;

FIG. 5 is a greatly enlarged bottom plan view thereof;

FIG. 6 is a greatly enlarged top plan view thereof;

FIG. 7 is a top perspective view of a ceiling fan shroud,
showing a second embodiment of my new design;

FIG. 8 is a bottom perspective view of FIG. 7;

FIG. 9 is a top perspective view of FIG. 7;

FIG. 10 is an enlarged side elevational view of FIG. 7,
the opposite side being a mirror image of that shown;

FIG. 11 is a greatly enlarged bottom plan view of FIG.
7; and,

FIG. 12 is a greatly enlarged top plan view of FIG. 7.
